UNITED STATES PATENT OFFICE.

GEORGE F. CULLEN, OF TRAIL, BRITISH COLUMBIA, CANADA.

MALLET.

Application filed December 4, 1923, Serial No. 678,494.

To all whom it may concern:

Be it known that I, GEORGE F. CULLEN, a subject of the King of Great Britain, residing at Trail, in the Province of British Columbia and Dominion of Canada, have invented certain new and useful Improvements in Mallets, of which the following is a specification.

This invention relates to certain new and useful improvements in mallets, and has particular reference to an improved form of mallet or hammer provided with renewable or removable impact receiving members.

15 The primary object of the invention is to provide a hammer with removable relatively soft impact receiving members that are so secured to the body of the hammer head as to permit their ready removal or replacement in an expeditious manner when found necessary.

Another object of the invention is to generally simplify and improve hammer heads that embody a body portion having removable impact receiving members upon the ends thereof.

25 A further object of the invention is to provide a hammer head including a body portion and relatively soft or yielding impact receiving members upon the ends of the body, and means to effectively detachably secure the impact receiving members upon the ends of the body whereby the impact receiving members may be readily and expeditiously removed or replaced from time to time, and in such manner that the impact received by said impact receiving members will be effectively transmitted to the body portion of the hammer head when in use.

30 Other objects will appear as the nature of the invention is better understood and the same consists in the novel form, combination, and arrangement of parts herein-
45 after more fully described, shown in the accompanying drawings, and claims.

50 In the drawings, wherein like reference characters indicate corresponding parts throughout the several views:

Figure 1 is a side elevational view of a mallet or hammer constructed in accordance with the present invention.

55 Figure 2 is a longitudinal transverse sectional view, taken substantially upon the line 2-2 of Figure 1.

Figure 3 is a view similar to Figure 2,

taken on a line of section, the plane of which is at right angles to the plane of the line of section of Figure 2.

Figure 4 is a transverse sectional view, 60 taken substantially upon the line 4-4 of Figure 1.

Figure 5 is a perspective view of the body portion of the hammer head.

Figure 6 is a perspective view of one of 65 the catches employed for holding the impact receiving members upon the body of the hammer head.

Figure 7 is a perspective view of one of the impact receiving members, and

70 Figure 8 is a view similar to Figure 7 of the other impact receiving member.

Referring more in detail to the drawing, the present invention embodies a hammer or mallet head, including a cylindrical hard 75 metal body portion 5 that is provided with a transverse opening as at 6, in which one end of an ordinary form of hammer handle 7 is suitably secured in any well known or preferred manner such as by means of 80 wedges 8 driven into the end of the handle 7 at one side of the body as shown in Figure 3.

The body portion 5 is provided with a transverse opening at each side thereof as 85 indicated at 9, which openings are in transverse alignment with each other, and pairs of transversely aligned openings are provided above and below the openings 9, as indicated at 10 and 11, respectively. The 90 body 5 is further provided with a longitudinal, relatively large opening 12, that is of sufficient width to extend beyond opposite sides of the handle 7 where the latter passes thru the body and arranged within the 95 opening 12 at opposite sides of the handle are catches including plates 13 arranged longitudinally of the body 5 and having rigid pins upon the ends thereof projecting outwardly thru the adjacent openings 100 10 and 11 as indicated at 14. Each plate 13 carries a central knob or finger piece 15 that projects outwardly through the adjacent opening 9, and the plates 13 are normally separated by means of helical compression springs 16 interposed between the ends thereof, whereby said plates are 105 yieldingly held in their normal positions into contact with the sides of the walls of the openings 12, as indicated in Figure 2. The 110 springs 16 are retained in place by engaging the ends thereof over inward exten-

sions or reduced projections provided as at 17 upon the inner ends of the pins 14 and when the plates are in their normal separated positions, the ends of the pins 14 project outwardly beyond the outer surface of the hammer body 5 for a purpose which will presently become apparent.

Impact receiving members are disposed upon opposite ends of the body 5, and one of the same includes a sleeve 18 that has a bore portion at one end sufficiently large to permit this end of the sleeve to snugly slide onto one end of the body as shown in Figure 2, the inner end of the sleeve 18 being provided with opposed side openings as indicated at 19 in Figure 7, into which the pins 14, at this end of the hammer body normally project, for detachably retaining this impact receiving member in place. The sleeve 18 has its bore of smaller diameter at its outer end and fitted tightly and immovably within the outer end of the sleeve 18 is a tip 20 of this impact receiving member which is preferably of cylindrical form and constructed from some suitable relatively soft or yielding material, such as leather, fiber, wood, or the like.

The other impact receiving member includes a sleeve 21 whose internal diameter is uniform throughout and of such size as to enable the inner end of said sleeve to be snugly fitted over the remaining end of the body 5 as shown in Figure 2, the inner end of said sleeve 21 being provided with transversely aligned openings 22 into which the adjacent pair of pins 14 are normally projected for holding this impact receiving member in place upon the body of the hammer head. Secured within the outer end of the sleeve 21 by a driving fit is another tip 23 that is formed of material similar to the tip 20 but whose diameter is larger than that of the latter. Thus, a small sized impact receiving surface or tip is provided at one end of the hammer body, while a larger sized impact receiving surface or tip is provided at the other end thereof so that the hammer may be effectively employed for different occasions requiring different sized tips.

The ends of the body 5 are internally rabbeted as indicated at 24, so as to form a circular seat upon which hard metal discs 25 are removably secured by means of screws 26 or the like, the inner ends of the tips 20 and 23 being seated against the outer sides of the discs 25 when the impact receiving members are secured upon the ends of the body as shown clearly in Figures 2 and 3.

This insures transmission of the impact or blows from the tips to the body portion in a uniform manner, so that the device will effectively serve purpose for a long continued period of use. By providing the remov-

able discs 25, the catches and their springs may be readily inserted within the body 5 or removed therefrom, and thus a structure is presented that may be readily assembled for convenient quantity production as well as taken apart for removal of the several parts thereof in case of damage to the same requiring renewal of such parts.

A hammer or mallet constructed as above described will be particularly useful to mechanics in the removing of gears or the like from shafts or straightening mud guards of motor vehicles and other similar operations, without marring, scarring or otherwise damaging these parts or machine elements.

In order to remove the impact receiving members, it is simply necessary to engage the buttons 15 by the thumb and forefinger and press the same toward each other whereby the plates 13 are moved inwardly against the action of the springs 16 for withdrawing the pins 14 from the openings 19 and 22 of the sleeves 18 and 21, after which the impact receiving members may be readily slid off of the ends of the body. A reversal of this operation will result in securing of the impact receiving members in place upon the ends of the body.

From the foregoing description, it is believed that the construction and operation, as well as the advantages of the present invention will be readily understood and appreciated by those skilled in the art.

What I claim as new is:

1. In a mallet or hammer, a hammer head including a body with removable impact receiving members upon the ends thereof, said body having a transverse opening within which an end of a handle is adapted to be secured, each of said impact receiving members comprising a sleeve having its inner end removably fitted upon the adjacent end of the hammer body and having a plug of yielding material permanently secured in the outer end thereof, means carried by the hammer body and engaged with the sleeves of the impact receiving members for retaining the latter in place upon said body, said body having a longitudinal opening intersecting the handle receiving opening, and said securing means comprising spring pressed catches disposed within said longitudinal opening at opposite sides of the body.

2. In a mallet or hammer, a hammer head including a body with removable impact receiving members upon the ends thereof, said body having a transverse opening within which an end of a handle is adapted to be secured, each of said impact receiving members comprising a sleeve having its inner end removably fitted upon the adjacent end of the hammer body and having a plug of yielding material permanently secured in

the outer end thereof, means carried by the hammer body and engaged with the sleeves of the impact receiving members for retaining the latter in place upon said body, 5
said body having a longitudinal opening intersecting the handle receiving opening, and said securing means comprising spring 30
pressed catches disposed within said longitudinal opening at opposite sides of the body, and removable rigid discs closing the ends of the body and against the outer surfaces of which the inner ends of the plugs 35
of the impact receiving members seat, said catches embodying pairs of outwardly projecting pins and intermediate finger pieces rigidly connected together, and said body having a plurality of openings in the sides 40
thereof through which said pins and knobs project into engagement with the sleeves of the impact receiving members.

3. In a mallet or hammer, a hammer head 15
including a body with removable impact receiving members upon the ends thereof, said body having a transverse opening within which an end of a handle is adapted to be secured, each of said impact receiving members 20
comprising a sleeve having its inner end removably fitted upon the adjacent end of the hammer body and having a plug of yielding material permanently secured in the outer end thereof, means carried by the 25
hammer body and engaged with the sleeves of the impact receiving members for retaining the latter in place upon said body,

said body having a longitudinal opening intersecting the handle receiving opening, and said securing means comprising spring 30
pressed catches disposed within said longitudinal opening at opposite sides of the body, and removable rigid discs closing the ends of the body and against the outer surfaces of which the inner ends of the plugs 35
of the impact receiving members seat, said catches embodying pairs of outwardly projecting pins and intermediate finger pieces rigidly connected together, and said body having a plurality of openings in the sides 40
thereof through which said pins and knobs project into engagement with the sleeves of the impact receiving members.

4. A hammer head comprising a body having impact receiving members upon the 45
ends thereof, said impact receiving members including yielding tips, and spring pressed catches mounted within the body and engageable with the impact receiving members for detachably retaining the latter upon the 50
ends of the body.

In testimony whereof I affix my signature.

GEORGE FREDERIC CULLEN.
